WARP BEAM FOR LOOMS

William A. Blanchard, Millbury, Mass., assignor to Crompton & Knowles Loom Works, Worcester, Mass., a corporation of Massachusetts

Application July 17, 1948, Serial No. 39,210

19 Claims. (Cl. 242—124)

1

This invention relates to improvements in warp beams and it is the general object of the invention to provide a beam head which is compact and so constructed that the warp engaging flange can be mounted accurately on and held firmly to the beam barrel.

The warp of a loom is wound on a so-called beam between heads or flanges on a barrel. The beam is rotatably mounted so that it can turn during loom operation to deliver the warp for the weaving operation. When large diameters of warp are required considerable difficulty is experienced in holding the warp heads firmly to the barrel and also keep their warp engaging surfaces true with respect to the axis of the barrel.

It is an important object of the present invention to provide a warp head constructed essentially of two parts or members having interengaging conical surfaces which can be drawn together to compress one of the parts against the barrel and wherein the warp engaging member derives support from the member on the barrel to resist deflection as the diameter of the warp increases during the winding operation.

It is a further object of the invention to provide a clamping member having a preferably conical compressible sleeve extending along the barrel for compression by a complementarily formed part of the warp flange and having also a rim or periphery to engage the warp flange at an appreciable distance from the surface of the barrel.

It is a further object of the invention to make the two members of the warp head in such manner that they can be assembled in but one relative angular position.

It is a still further object of the invention to provide a warp head including a clamp member and a warp engaging member each having conical surfaces which are drawn along each other and are guided by mutually engaging surfaces to maintain the warp engaging member in correct position with respect to the barrel during the assembly of the head.

With these and other objects in view which will appear as the description proceeds, the invention resides in the combination and arrangement of parts hereinafter described and set forth.

In the accompanying drawings, wherein two forms of the invention are set forth,

Fig. 1 is an elevation of an empty warp beam made according to the preferred form of the present invention, parts being broken away,

Fig. 2 is an end elevation looking in the direction of arrow 2, Fig. 1,

Fig. 3 is an enlarged vertical longitudinal section on line 3—3, Fig. 2,

2

Fig. 4 is a fragmentary side elevation looking in the direction of arrow 4, Fig. 3.

Fig. 5 is a transverse vertical section on line 5—5, Fig. 3,

Fig. 6 is an enlarged section on line 6—6, Fig. 4, and

Fig. 7 is a view similar to a portion of Fig. 3 but showing a modified form of the invention.

Referring to Figs. 1 to 6 which show the preferred form of the invention, the beam comprises a cylindrical preferably tubular barrel 10 which in the preferred form is smooth throughout its length. The warp (not shown) is wound on the barrel between two heads H, and since they are alike only one of them will be described in detail, namely, the head at the left end of the barrel as viewed in Fig. 1.

The head is formed of two parts or members one of which is a warp engaging member 11 and the other of which is a clamping member 12. The latter is formed with a disk or web 13 the outer part of which is formed with a flange 14 having a preferably cylindrical rim or periphery 15. Integral with the web 13 is a conical hub or sleeve 16 extending along the barrel and divided into at least two sectors which can be deflected toward the barrel. As shown in Fig. 5, the hub has two slots or saw cuts 17 and 18 which divide the sleeve 16 into two sectors 19 and 20.

The flange 14 is provided with a recess 21 across which extends a lug 22 in which is threaded a spreading or expanding screw 23. The left end of the screw, Fig. 4, abuts a surface 24 at the left end of the recess 21, and the flange is provided with a slot 25 which is open at periphery 15 and may be radial as suggested in Fig. 4. The slot 25 and screw 23 which extends across it are not essential to certain features of the invention, and can be omitted if desired.

The warp head member 11 has a flat warp engaging surface 30 formed on a flange 31 which has cast integral therewith a hub 32 formed with an internal cylindrical surface 33 to engage the peripheral cylindrical rim 15 of the clamp member. Extending between the hub 32 and the flange 31 are several reinforcing gussets 34.

The warp head member 11 is formed with an internal conical bore 35 which extends along and complements an external conical surface 36 on the sleeve 16. Draw screws 37 pass through the flange 14 and are tapped or threaded as at 38 into the warp head member 11. There may be several of these draw screws 37 as suggested for instance in Fig. 2, and it will be noted that they are unevenly distributed angularly around the axis of the barrel so that there is but one angu-

lar position which the members 11 and 12 can have with respect to each other. While this relationship of the screws is desirable it is not essential in order to take advantage of all the features of the invention. The heads 39 of the screws 37 may be housed within pockets 40 of somewhat larger size, as suggested for instance in Figs. 3 and 4.

Separating screws 42 are threaded into the clamping member 12 and have their ends adapted for engagement with the head member 11, as at 43 (see Fig. 3). Ordinarily these separating screws will be backed off so that they do not engage the member 11, but when it is desired to separate the two members 11 and 12 the separating screws will be turned in to release the conical surfaces 35 and 36.

In the manufacture of the warp head the two members 11 and 12 may be drawn together by tightening the draw screws 37 to force the sectors 19 and 20 against a stub shaft having the same diameter as that of the beam barrel 10. If screw 23 is used it will be turned to expand surface 15 against surface 33. The face 30 is then turned true to the axis of the stub shaft, after which loosening of the screws 23 and 37 and manipulation of screws 42 will effect separation of the conical surfaces 35 and 36, thus permitting removal of the head from the stub shaft (not shown). It is desirable that the two members 11 and 12 of the head remain connected to each other by means of the draw screws 37 after finishing of surface 30, but it will be understood that this is not essential.

When a warp is to be wound on the barrel 10 the heads H will first be located along the barrel at the required distance apart, the screws 37 being slack to permit end adjustment, and screw 23 being loose. The screws 37 are then tightened to force the internal conical surface 35 against the external conical surface 36 of the sleeve 16, thereby forcing the sectors 19 and 20 tightly against the barrel 10. During this relative movement of members 11 and 12, surface 15 on member 12 guides surface 33 on member 11 to prevent twisting thereof. The expansion screw 23 will then be turned in such direction as to separate parts 48 and 49 of member 12 on the sides of slot 25 to force peripheral rim 15 of flange 14 against the internal surface 33 of the hub 32. The surfaces 15 and 33 are preferably cylindrical and concentric with the axis of the barrel, and it will be understood that the conical surfaces are peripherally coaxial with the barrel. Tightening of the expansion screw 23 will establish a tight fit between the flange 14 and the hub 32 so that the member 11 is supported not only by the sleeve 16, but also by the flange 14. The surface 15 is a considerable distance from the barrel 10 as will be seen in Fig. 3.

As shown in Fig. 1 the barrel in the preferred form of the invention has a smooth cylindrical surface which fits the smooth bore of sleeve 16. The invention, however, is not limited to a smooth barrel, and in the modified form of the invention the barrel can be provided with screw threads 58, as shown in Fig. 7. When screw threads are used on the barrel 10 the internal bore of the sleeve 16 will be similarly threaded, as at 51.

From the foregoing it will be seen that the invention provides a compact warp head occupying a small space along the length of the beam barrel 10. The two members 11 and 12 have coacting complementary tapered or conical surfaces which can be drawn together by drawing means,

such as screws 37, to clamp the sectors 19 and 20 against the beam barrel by forces transmitted through conical surfaces 35 and 36. Conical surfaces 35 and 36 diverge outwardly from the barrel and toward flange 14 of the clamping member. The peripheral rim 15 supports the hub 32 at points spaced from the surface of the barrel 10, the clamp member 12 in this respect affording support for the member 11 along spaced zones one of which is close to the barrel and a conical form and the other of which is spaced from the barrel and preferably of cylindrical form. During the drawing together of the two members of parts 11 and 12 the relative sliding movement parallel to the barrel 10 of periphery 15 of the clamping member flange 14 and surface 33 on hub 32 guides the warp head member 11 to keep it from twisting or moving in such manner that the surface 30 will become oblique with respect to the barrel axis. While the expanding screw 23 and slot 25 can be used as set forth herein to expand the periphery 15 of the clamping member, they may be omitted. When used, however, the expanding screw permits the establishment of a very tight fit between the periphery 15 and the cylindrical surface 33 of the hub 32, and this fit together with that existing at the conical surfaces holds the beam head member 11 rigidly in position with respect to the clamp member 12.

Having thus described the invention it will be seen that changes and modifications of the foregoing specific disclosure may be made without departing from the spirit and scope of the invention.

What is claimed as new is:

1. In a warp beam having a cylindrical barrel, a warp head member having a flat warp engaging face, a clamping member on the barrel, said members having engaging cylindrical surfaces spaced from and concentric with the barrel and having also engaging conical surfaces coaxial with the barrel, and means to draw said members together to cause the warp head member to exert forces through said conical surfaces to force a portion of said clamping member against the barrel, said cylindrical surfaces guiding the head member as the members are drawn together.

2. In a warp beam having a cylindrical barrel, a warp head member having a flat warp engaging face and having a cylindrical surface concentric with and spaced from the barrel and having also a conical surface coaxial with the barrel, a clamping member on the barrel having a cylindrical surface engaging the cylindrical surface of the warp head member and having also a conical surface complementing and engaging the conical surface of the warp head member, and means to draw said members together to cause the warp head member by forces transmitted through said engaging conical surfaces to force part of the clamping member against said barrel while said cylindrical surfaces move relatively to each other and guide the warp head member relatively to the clamping member.

3. In a warp beam having a cylindrical barrel, a warp head member having a flat warp engaging face and having an internal cylindrical surface concentric with and spaced from the barrel and having also an internal conical surface spaced from and coaxial with the barrel, a clamping member on the barrel having an external cylindrical surface engaging said internal cylindrical surface and having also an external conical surface coaxial with the barrel and complementing

and engaging said internal conical surface, and means to draw said members together and cause the warp head member by forces transmitted through said conical surfaces to force portions of the clamping member adjacent to said external conical surface against said barrel while the cylindrical surfaces guide said warp head member as the latter is drawn toward said clamping member.

4. In a warp beam having a cylindrical barrel, a warp head member having a flat warp engaging face, a hub on said member spaced from the barrel, a clamping member on the barrel, a flange forming part of said clamping member and engaging said hub, complementary tapered mutually engaging surfaces on said members inclined outwardly from the barrel toward said flange, and means to draw said members together to cause the warp head member by forces transmitted through said tapered surface to compress portions of the clamping member adjacent to the tapered surface thereof against the barrel while said hub slides along and is guided by said flange.

5. In a warp beam having a cylindrical barrel, a warp head member having a flat warp engaging face, a hub extending laterally from and integral with said member and concentric with and spaced from the barrel, a clamping member on the barrel having a flange engaging said hub, a sleeve integral with the flange and extending along the barrel, complementary mutually engaging conical surfaces on the warp head member and said sleeve, and means to draw said members together while said flange guides said hub to cause the warp head member by forces transmitted through said conical surfaces to force said sleeve against the barrel.

6. In a warp beam having a cylindrical barrel, a warp head member having a flat surface to engage the warp and having an integral hub provided with an internal cylindrical surface concentric with and spaced from the barrel and having also an internal conical surface coaxial with and spaced from the barrel, a clamping member on the barrel having a circular flange provided with an external cylindrical surface engaging said internal cylindrical surface of the hub, a sleeve integral with the flange extending along the barrel and having an external conical surface engaging and complementing said internal conical surface of the head member, and screw means for drawing said members together while the cylindrical surfaces engage each other to guide the warp head member relatively to the clamping member and effective to cause said warp head member by forces transmitted through said conical surfaces to force said sleeve against said barrel.

7. In a warp beam having a barrel, a warp head member having a flat warp engaging face, a clamping member on the barrel, said members having mutually engaging guide surfaces slideable relatively to each other in a direction parallel to the barrel, said members having also mutually engaging tapered surfaces, and means to draw said members together to cause the warp head member to exert forces through said tapered surfaces to force a portion of said clamping member against the barrel while said guide surfaces slide relatively to each other.

8. In a warp beam having a barrel, a warp head member having a flat warp engaging face, a clamping member on the barrel, said members having mutually engaging guide surfaces slideable relatively to each other in a direction parallel to

the barrel, said members having also mutually engaging surfaces tapered outwardly from the barrel in a direction away from said warp engaging face, and means to draw said members together to cause the warp head member to exert forces through said tapered surface to force a portion of said clamping member against the barrel while said guide surfaces slide relatively to each other, said means comprising a plurality of screws extending through the clamping member and threaded into the warp head member and disposed non-uniformly around the axis of the barrel.

9. In a warp head member for a warp beam having a barrel and a clamping member provided with cylindrical and conical surfaces spaced from and coaxial with the barrel, said head member including a warp engaging flange and having a cylindrical surface to engage the cylindrical surface of the clamping member and having also a conical surface to engage the conical surface of the clamping member.

10. In a warp head member for a warp beam having a barrel and a clamping member thereon formed with an external cylindrical surface and an external conical surface, both of said surfaces being coaxial with and spaced from the barrel, said head member comprising a warp engaging flange, a hub integral with the flange having an internal cylindrical surface to engage the external cylindrical surface of the clamping member, and said member having an internal conical surface to engage the conical surface of the clamping member.

11. A clamping member for a warp beam having a barrel and a warp head member formed with conical and cylindrical surfaces coaxial with and spaced from the barrel, said clamping member comprising a flange having a cylindrical surface to engage said cylindrical surface of the warp head member and having a sleeve for mounting on the barrel extending laterally from the flange and formed with a conical surface to engage the conical surface of the warp head member.

12. A clamping member for a warp beam having a barrel and a warp head member extending therearound formed with internal cylindrical and conical surfaces coaxial with and spaced from the barrel, said clamping member being formed with an external cylindrical surface to engage the internal cylindrical surface of the warp head member and having a sleeve formed with an external conical surface to engage the internal conical surface of the warp flange.

13. In a warp beam having a cylindrical barrel, a warp engaging head surrounding the barrel and having a cylindrical surface concentric with and spaced from the barrel and having also a conical surface coaxial with and spaced from the barrel, a clamp member having a circular flange located within the cylindrical surface and supported by the barrel and having a conical sleeve complementing and engaging the conical surface on said warp engaging member, means drawing said members together to cause said sleeve to be forced against the barrel by forces transmitted from the head through the conical surfaces, said flange having a part thereof formed to be expansible for engagement with said cylindrical surface on the head, and expanding means forcing said expansible part of the flange into tight holding relation with respect to said cylindrical surface.

14. In a warp beam having a cylindrical barrel, a warp engaging head having a hub concentric with and spaced from the barrel and having also

a conical surface coaxial with the barrel, a clamp member having a conical surface complementing and engaging the conical surface on the warp head, a circular flange forming part of said clamp member located within the hub and having a part thereof expandable toward the hub, means drawing said warp head and clamp member together to cause the warp head acting through said conical surfaces to force a part of the clamping member against the barrel, and means carried by the clamp member expanding said expandable part of the flange into close fitting relation with respect to the hub.

15. A clamping member for a warp beam having a barrel and a warp head member thereon formed with a hub spaced from and concentric with the barrel, the head member having a conical surface coaxial with the barrel, said clamping member comprising a circular flange formed with a surface to engage the hub and having an open slot therein extending inwardly from the periphery of the flange, expanding means on the clamping member engaging parts of the flange on opposite sides of the slot effective to move said parts away from each other, and a sleeve integral with the flange to extend along the barrel and having a conical surface to engage the conical surface of the head member.

16. A clamping member for a warp beam having a barrel and a warp head member thereon formed with a hub spaced from and concentric with the barrel, the head member having a conical surface coaxial with the barrel, said clamping member comprising a circular flange formed with a substantially circular surface to engage the hub and having an open slot therein extending inwardly from the periphery of the flange, an expanding screw threaded into part of the flange on one side of the slot and extending across the latter and engaging another part of the flange on the opposite side of the slot, said screw being turnable in a direction to cause separation of said parts of the flange, and a sleeve integral with the flange to extend along the barrel and having a conical surface to engage the conical surface of the head member.

17. A clamping member for a warp beam having a barrel and a warp head member thereon formed with a cylindrical surface concentric with the barrel and having a conical surface coaxial with the barrel, said clamping member having parts deflectable toward the barrel by forces

transmitted through said conical surface and having other parts formed with a periphery expandable to engage said cylindrical surface.

18. In a warp beam having a cylindrical barrel, 5 a warp head member having a flat warp engaging surface surrounding the barrel, a hub on said member spaced from the barrel and concentric therewith, a clamp member on the barrel secured to said head member and having a circular periphery lying within the hub and having a slot extending inwardly from said periphery toward but terminating short of said barrel, and expanding means screw threaded into a part of said clamp member on one side of said slot and extending across the latter and abutting another part of the clamp member on the opposite side of said slot and effective to separate said parts of the clamp member and force said periphery into tight holding relation with respect to said hub.
19. In a warp beam having a cylindrical barrel, 15 a warp head member having a flat warp engaging surface surrounding the barrel, a hub on said member concentric with and spaced from the barrel, a clamp member on the barrel within said hub secured to the head and having a circular periphery for engagement with the interior of said hub and having a slot extending inwardly from the hub toward but terminating at a point spaced from the barrel, and an expanding screw 25 extending transversely of the axis of the barrel screw threaded into a part of said clamp member at one side of the slot and extending across the latter and abutting another part of the clamp member on the opposite side of said slot and effective when tightened to expand said periphery by separation of said parts of the clamp member circumferentially of the latter to force said periphery into tight holding relation with respect 30 to the hub.
